UNITED STATES PATENT OFFICE.

JOHN T. HAWKINS, OF BROOKLYN, NEW YORK.

DELIVERY APPARATUS FOR PRINTING-PRESSES.

SPECIFICATION forming part of Letters Patent No. 225,280, dated March 9, 1880.

Application filed May 19, 1879.

To all whom it may concern:

Be it known that I, JOHN T. HAWKINS, of Brooklyn, in the county of Kings and State of New York, have invented an Improvement 5 in Delivery Apparatus for Printing-Presses, which improvement is fully set forth and illustrated in the following specification and accompanying drawings.

The object of the invention is to effect the 10 delivery of stiff paper or card-board with the same efficiency and facility as the delivery of thinner material or ordinary printing-paper; and the invention consists of a certain combination of friction-wheels and retaining-bands, 15 either with or without the addition of a fly-frame, with the impression-cylinder of a printing-press, and of certain adjustable sheet-stops placed upon the fly-fingers constituting the fly-frame of the machine, as is hereinafter 20 more fully set forth and claimed in detail.

In the accompanying drawings, Figure 1 is a sectional side elevation, and Fig. 2 a plan, of that form of printing-press which delivers the sheet or card from the top of the cylinder toward the front of the machine; and Figs. 3 and 4 are, respectively, a side view, partly in 25 section, and an under view, of a fly-finger.

In the said figures, the letters S S designate the side frames of the machine.

30 The letter C designates the cylinder; F, the feed-board, and F' the fly-board.

The letters f f designate the fly-fingers, which receive the sheet from the cylinder C.

The letters l l designate the lifter-fingers, 35 which lift the advancing edge of the sheet upon the fly-fingers f f.

The letters g g designate the grippers, which hold the sheet while being printed and release it at the time the lifter-fingers raise its ad- 40 vancing edge.

The letters a a designate arms secured to the rod R, upon which the fly-fingers rest when receiving the sheet. The small ends of the arms a a carry a small shaft, s, upon which are secured two narrow-faced pulleys or wheels, 45 p p. The arms a a are so adjusted as to allow the wheels p p to bear gently upon the surface of the cylinder C.

The wheels p p may be secured upon the 50 shaft s in any position, and they and the shaft s rotate by frictional contact with the cylinder

C, the journals of the shaft s turning in the ends of the arms a a.

The letters b b designate two narrow bands of metal, secured to a dovetail-formed bar, B, 55 upon the under side of the feed-board F. A part of each of said bands is made to conform to the circumference of the cylinder C, and the bands themselves are adjustable laterally upon the bar B. 60

The mechanism for imparting motion to the cylinder, grippers, lifter-fingers, and fly-fingers, not being necessary to the illustration of the invention, is not shown in the drawings.

The letters T T designate stops secured to 65 two or more of the fly-fingers, as shown. Said stops form an inclined plane, up which the paper passes on its way to and upon the fly-fingers. The lifter-fingers l l and fly-fingers f f are made with split sockets, grasping 70 smoothly-turned rods, in order that said fingers may be readily adjusted, *inter se*, either angularly or laterally.

By means of this construction the grippers, 75 lifter-fingers, and fly-fingers severally move within or between each other, and require to be so adjusted that the said parts may be so placed as not to come into contact with each other, and in different positions for varying widths of sheets to be printed and delivered; 80 but the inter-adjustability, *per se*, of these parts I do not claim.

In the printing of card-board or stiff paper and delivering the same from this form of press, such stiff material straightens out after 85 printing, and does not cling sufficiently to the cylinder after being released by the grippers to carry it to and upon the fly-fingers, the card or stiff paper falling back at b upon the form, unless released by the grippers before arriving 90 at b, and taken from the cylinder by hand or some special mechanism. It is desirable, therefore, to deliver card-board upon the fly with equal facility and by means of the same devices that are employed to deliver thinner material. In order to accomplish this desirable 95 end, the wheels p p are provided, as above explained, and by their pressure upon all sheets of whatever material passing through the machine, keep said sheets in contact with the 100 cylinder, the grippers opening and releasing the advancing edge of each sheet after said edge

has passed under the wheels *p p*. Said wheels continue to press upon the sheet, causing the friction of the cylinder's surface to drive the paper under them and fully upon the fly.

5 The momentum of each sheet of paper or card carries its following edge beyond the stops *T T*, which stops prevent the cards or paper from being thrown off the fly by centrifugal action as the fly is rapidly rotated over

10 to the fly-board *F'*.

The bands *b b* are placed immediately in front of the wheels *p p*, and both are so placed as to run upon the unprinted margins of the paper. The function of the bands *b b* is to prevent stiff card-board from coming in contact, on its printed side, with the under side of the feed-board, and, as said bands touch only the margins of a sheet, neither they nor the wheels *p p* can mar the perfection of the

20 work.

Having thus fully explained the construction and operation of my said improvement in delivery apparatus for printing-presses, as of my invention, I claim—

1. The combination, with the fly-fingers *ff*, 25 of the adjustable stops *T T* near the outer ends of said fingers, whereby centrifugal action upon the sheets of paper in process of delivery is prevented, substantially as set forth.

2. In combination with the cylinder *C*, the 30 retaining bands *b b* and friction-wheels *p p*, substantially as and for the purposes set forth.

3. In combination with the cylinder *C*, the retaining-bands *b b*, friction-wheels *p p*, and fly-fingers *ff*, provided with stops *T T*, sub- 35 substantially as and for the purposes set forth.

JOHN T. HAWKINS.
